UNITED STATES PATENT OFFICE

HARRY P. COE, OF NEW YORK, N. Y., ASSIGNOR TO FLORENCE A. COE, OF SCARSDALE,
NEW YORK

DRYING MACHINE FOR LUMBER AND THE LIKE

Application filed May 19, 1925, Serial No. 31,275. Renewed May 15, 1930.

My invention relates to a drying machine for lumber or other slab-like material.

It is the general object of the invention to improve the construction of a drying machine of the character described and to provide a machine which will quickly and effectively dry lumber and the like to the desired degree of dryness.

It is a more specific object to provide a machine in which lumber or other material may be fed therethrough at a variable rate.

It is a further object to provide a drying machine of the character indicated with means for conditioning lumber or other material passing therethrough.

Briefly stated, in the preferred form of the invention I employ a housing extending substantially the full length of the machine. In the housing there are a plurality of tiers of feed rolls for conducting several tiers of lumber or the like therethrough. Each tier of feed rolls may be driven by a separate and independent driving means, such as a variable speed motor, whereby one tier may be driven at a different speed from every other tier, and this rate of speed may be varied at will. The feed rolls in general are preferably rather light and serve merely to cause the boards to progress from one end of the machine to the other. However, at some point in the travel of the material I may provide a plurality of very heavy or mechanically pressed rolls, which may straighten out warped lumber or the like and cause the same to dry flat. Just before or during this heavy pressing operation, the lumber is preferably conditioned by showering the same with wet steam or water, so as to render the same less liable to crack or check during the straightening process. A pan or reservoir for water may be provided in the bottom of the housing at one or more points, and vapor rising from this reservoir will condition the lumber somewhat and tend to prevent case hardening. Hot air or other drying medium may be introduced at opposite sides of the housing through vertically extending pipes which merge into a header extending longitudinally of the housing at each side thereof. Steam pipes may be positioned inside of the housing

so as to further assist in heating and drying the lumber during passage through the housing.

In the drawings which show, for illustrative purposes only, a preferred form of the invention—

Fig. 1 is a diagrammatic view of a part of a drying machine, including the delivery end and illustrating features of the invention;

Fig. 1^a is a view similar to Fig. 1, but showing the entrance end of the machine;

Fig. 2 is a fragmentary view in side elevation of the delivery end of the drying machine;

Fig. 3 is a transverse sectional view through the machine;

Fig. 4 is a sectional view taken substantially in the plane of the line 4—4 of Fig. 3;

Figs. 5 and 6 are views of arrangements of steam piping in the machine.

The machine includes a housing designated generally 5, which housing may have hinged doors or the like 6—6, which may be opened for inspection of the interior. The housing and interior parts are mounted on a substantial concrete base or foundation 7, and the top of the housing may have one or more sloping hoods 8 discharging into stacks, such as 9, for conducting away the vapors evolved during the drying process.

In the interior of the housing are a plurality of feed rolls 10—10, which may be arranged in several tiers. These rolls are journaled in suitable uprights 11—11, the bearing for one of the rolls in each pair in a tier being in the form of a slot 12 for permitting variation in the distance between the rolls for receiving material of different thicknesses. One of the rolls of each set in a tier is provided with a sprocket 13, over which the driving chain 14 runs and serves to drive the rolls. As shown particularly in Fig. 2, each of the five tiers of rolls shown in the drawings is driven by a separate motor 15. In the particular form shown the motor 15, by means of a chain 16, drives the chain 14 through a suitable reduction gear mechanism 17. The utility of driving each separate tier by a separate and independent variable speed device, such as a motor, is that

lumber or the like of different thicknesses may be run through the machine at the same time, without danger of overdrying thin lumber and underdrying thicker lumber, and this variation may be accomplished during the time that the machine is running without the necessity of having to shut down the machine for the purpose of changing the size of the driving sprocket or other means, which 10 has previously been done when it was desired to change the rate of speed of feed rolls.

The majority of the feed rolls 10—10 in the machine are relatively light rolls, which serve merely to progress the lumber on its 15 course. However, some of the rolls, such as those indicated at 20—20 in Fig. 1^a, may be very heavy or mechanically pressed rolls, for exerting a high pressure on the material passing between them for the purpose of straightening out warped boards and causing the same to dry in a flat condition. With some material it is desirable to steam or moisten it before or during the time it is passing between the heavy rolls 20. For this purpose I have indicated pipes 21—21, having discharge apertures facing the material passing between the rolls 21—21 for the purpose of discharging steam or moisture onto the boards, for rendering the same less liable 30 to crack and check during the straightening operation.

The entrance rolls 22—22 shown in Fig. 1^a are preferably single rolls, that is, not paired with other rolls, so that the lumber feeder 35 may feed a board a substantial distance into the machine without having to wait for the mechanically operated rolls to feed the same inwardly.

In order to dry lumber passing through 40 the machine hot air or hot products of combustion may be introduced into the housing. For that purpose conduits 25—25 may be provided at the lower side of the housing and at opposite sides thereof. These conduits may 45 be fed from the same or separate sources of drying mediums.

At suitable intervals upstanding pipes or risers 26—26 extend from the conduits 25 for the purpose of conducting hot air upwardly into the housing. The risers 26—26 may have suitable openings 27—27 either permanently open or valve controlled, for introducing the drying medium into the housing and onto the material being dried. In order to 55 further heat the material passing through the machine I position steam pipes therein over a substantial part of the interior.

Figs. 5 and 6 illustrate two methods of steam pipe arrangement. Headers 30—30 60 may be arranged in the housing, one being an inlet header and the other an outlet header, and between these headers are a plurality of lateral pipes 31—31, which conduct the steam 65 in the housing and serve as radiating surfaces. The headers 30 may be connected at

the outside of the housing to the main steam supply pipe 32 and to a corresponding steam exhaust pipe not shown (see Fig. 3).

Fig. 6 illustrates a modification in which the steam pipes are arranged in what may be termed series, rather than in parallel, as shown in Fig. 5.

Now, in order to further condition the lumber passing through the housing and to prevent the same from case hardening, I 75 may provide an open reservoir 35 in the bottom of the housing at a suitable point, and the heat in the housing causes water vapors to rise from the reservoir 35 and to moisten the lumber so as to prevent case hardening and permit the same to be properly dried.

If the hot gases from the conduits 25—25 are very dry it may be desirable to humidify the same so as to prevent the material from being dried too quickly or case hardened. In order to properly humidify the drying agent and also to conserve heat I may return a part of the vapor laden gases from one or more of the hoods 8 or stacks 9 to the housing and for that purpose I have indicated a conduit 35 connecting the conduit 25 with a part of the housing carrying vapor laden gases, as the hood 8 (Fig. 3). A blower 36 may be employed to force the vapors from the hood to the conduit 25. This conduit may be controlled by a valve 37. Obviously the conduit 25 at the opposite side of the machine may be similarly connected to the hood or stack.

The operation of the machine will now be clear. Lumber is fed onto the single feed rolls 22 (Fig. 1^a) and is then fed either directly or at a later time during its passage through the machine to the heavy pressure rolls 20—20, where it is straightened out. Steam from the pipes 21—21 may at this time serve to moisten the lumber, to facilitate the straightening process. Lumber is then fed by the rolls 10 on through the machine at the proper rate of speed, so that when it reaches the discharge end it has dried the desired amount. The time for drying will be determined principally by the length of the machine, the rate of speed of travel therethrough, the quantity of moisture originally contained in the lumber, the thickness thereof, the quantity and character of heating medium supplied to the machine and the dryness or moisture content desired in the dried product.

By the provision of variable and independent speeds for the various tiers of rolls, lumber of different dryness and different thickness may be fed through separate tiers, and the speed of travel so regulated that when the lumber reaches the outlet or discharge end it will all be in substantially the desired condition of dryness.

The steam discharge means in the housing, as well as the provision of the reservoir for 130

generating water vapor, both serve to condition the lumber so as to prevent case hardening so that the lumber may dry substantially without checks or cracks. The moisture given off by the lumber being dried, as well as the gaseous material fed into the housing, pass into the hoods 8 and out through the stack 9 or when desired a part may be recirculated through the housing as previously described.

5 10 Obviously the principles of the invention are applicable to a machine having a single deck or tier of rolls or a plurality of such decks or tiers and I do not wish to be confined to a multiple deck machine except where 15 I have so indicated.

Ordinarily the enclosing housing would be insulated with suitable insulation to conserve the heat used for drying the lumber.

20 While the invention has been described in some detail, I do not wish to be limited strictly to the forms shown, since changes may be made within the scope of the invention as defined in the appended claims.

I claim:

25 1. In a lumber drying machine, a housing, a plurality of tiers of feeding rolls therein, means for driving said feeding rolls for feeding material to be dried through said housing, a drying medium conduit extending longitudinally of said housing and at the lower end thereof, a plurality of upstanding tubes connected to said conduit and having openings for discharging heating medium into said housing, a stack for conducting vapors 35 from said housing, means for discharging a humidifying agent into said housing, pairs of pressure rolls for straightening the material while subjected to said heating medium and humidifying agent, and heating means within said housing for heating lumber 40 passing therethrough.

2. In the combination defined in claim 1, said means for driving said feeding rolls serving to drive one tier of feeding rolls at a 45 speed different from the speed of another of said tiers.

HARRY P. COE.
